UNITED STATES PATENT OFFICE.

ARTHUR D. SKILLMAN, OF LOS ANGELES, CALIFORNIA, ASSIGNOR TO
AMERICAN SWITCH AND SIGNAL COMPANY, OF LOS ANGELES,
CALIFORNIA, A CORPORATION OF ARIZONA TERRITORY.

AUTOMATIC CAR-STOPPING DEVICE.

No. 822,161.

Specification of Letters Patent.

Patented May 29, 1906

Application filed July 24, 1905. Serial No. 270,918.

To all whom it may concern:

Be it known that I, ARTHUR D. SKILLMAN, a citizen of the United States, residing at Los Angeles, in the county of Los Angeles and State of California, have invented a new and useful Automatic Car-Stopping Device, of which the following is a specification.

This invention relates to car apparatus for operating in conjunction with block systems or protecting devices for crossings, switches, bridges, &c., for automatically controlling the operation of the car.

One object of the invention is to stop the car by automatically opening the circuit through the motor independently of the car-controller or in a locomotive to automatically shut the throttle-valve independently of the throttle-lever, thus in either example preventing the motorman or engineer from interfering.

Another object is to automatically shut off the power and apply the brakes and, preferably, incidentally operate a signal-whistle when the car moves into conjunction with the first-met unit of the track system in danger position and to allow the motorman or engineer to restore the power and release the brakes from his position at the controller or in the cab after the car has passed the next unit, provided the latter is not in danger position, thus automatically checking the progress of the train when it comes into a danger zone, but allowing the train to proceed at the discretion of the engineer as far as the next unit.

Another object is to remove the control entirely from the engineer at the said second-met unit if that unit is in danger position and to bring the train to a stop, and before the train can again proceed to require a resetting of the apparatus from the ground.

Another object is to maintain the control of the train from the cab or motorman's post if the said second-met unit is not in danger position and to cause the train-stopping apparatus to automatically reset or clear itself when the said second-met unit is not in danger position, so that the train can proceed.

It is often desirable to run a train at a slow speed over certain sections of the track—such, for instance, as through cities, or yards, or in places where the track or bridges are being repaired—and a further object is to

provide for automatically causing the train to be checked in its movement over such sections. In checking the movement of trains through yards, for example, permanently-located trips or track devices may be employed for co-operating with the car-controlling mechanism, and in places where, for example, repairs are being made temporary trips or track devices may be applied to the track for co-operating with the car-controlling mechanism.

There are places where it is impracticable to flag a train in the ordinary manner—such, for example, as on a long trestle or in a tunnel—and in such cases one or more trips or track devices may be temporarily placed on the track at the desired points, which by co-operating with the car-stopping mechanism will automatically check or stop, as desired, the train when it arrives at the track devices.

The accompanying drawings illustrate the invention, and, referring thereto, Figure 1 is a side elevation of a truck, part of the track and part of a car equipped with the train-stopping mechanism, the air-brake cylinder and connections thereto being removed. A manually-controlled unit forming part of a block system is illustrated in danger position. Fig. 2 is a plan view of what is shown in Fig. 1, the car-wheels being removed and the brake-cylinder, valve, and connections therefor being shown. Fig. 3 is an enlarged cross-section through the controlling mechanism on the line $x^3 x^3$, Fig. 4. Fig. 4 is a cross-section on the line $x^4 x^4$, Fig. 3. Fig. 5 is a cross-section on the line $x^5 x^5$, Fig. 4. Fig. 6 is a cross-section through the controlling-valve, taken on the line $x^6 x^6$, Fig. 4. Fig. 7 is a similar view on the line $x^7 x^7$, Fig. 4. Fig. 8 is a sectional view through the rear end of a locomotive, showing the invention applied to a locomotive for controlling the throttle-lever and throttle. Fig. 9 is an elevation looking in the direction of the arrow, Fig. 1, of the circuit-breaker and the mechanism for controlling the same. Fig. 10 is a side elevation of the circuit-breaker shown in Fig. 9. Fig. 11 is a detail in perspective of the controlling arm and pawl for operating the pawl-carrier.

The train-stopping apparatus is designed for use with either automatic block systems or those which are manually controlled or for

coöperation with permanent or temporarily-placed trips or track devices. For the sake of simplicity a manually-controlled trip or protective track device has been shown, and, referring to Fig. 1, 1 designates a trip-lever which may be preferably pivoted to one of the track-rails 2 on the inside thereof, so as to be in line with the flanges of the car-wheels. The trip-lever 1 rests upon a flat spring 3, the position of which is controlled by a pivoted lever 4, which is connected by a rod 5 with a hand-lever 6. When the hand-lever 6 stands over, as shown in Fig. 1, the lever 4 is held vertical, and the trip-lever 1 is yieldingly held with its end projecting slightly above the track-rail by the spring 3. That element of the train-stopping device which coacts with the trip-levers is preferably located back of the front wheel of the car, so that it is shielded by the car-wheel. The spring 3 is weak enough to yield and allow the trip-lever 1 to be depressed by the car-wheel; but the spring is strong enough to hold the trip-lever with sufficient strength to cause the train-stopping device to be operated thereby. The most convenient place to mount the main part of the car-stopping devices is on the equalizing-bar 7 of the car-truck; and fastened thereto is a bracket 8, which supports a shaft 9. Also mounted on the equalizing-bar 7 is a box 10, in which is housed the mechanism about to be described, and projecting through the box 10 is a shaft 11. Mounted on the shafts 9 and 11 are arms 12 and 13, the lower ends of which are pivotally attached to an operating-shoe 14, the arm 13 being a trifle shorter than the arm 12, so that the front end of the operating-shoe 14 is higher than its rear end. The operating-shoe 14 is suspended directly behind the flange of the front wheel of the truck and in line with the trip-lever 1, and when it is moved over a raised trip-lever the operating-shoe is swung rearwardly and upwardly, thus rocking the shaft 11. Mounted loosely on the shaft 11 is a pawl-carrier 15 with a segmental recess 16, the shaft 11 having a lug 17, which projects within the recess 16. An arm 18, which projects from the pawl-carrier, has pawls 19 and 20. The pawl 19 actuates an eight-toothed ratchet 21, which is mounted on a valve-shaft 22. One end of the valve-shaft 22 has a bevel-gear 23, which meshes with a bevel-gear 24 on a vertical shaft 25. Fastened on the valve-shaft 22 by a pin 26 is a tapered valve-plug 27, which lies in a casing 28, having a tapered bore, the plug 27 being held with a close fit therein by a compression-spring 29. The plug 27 has two independent valves A and B, fixed with relation to each other. The two valves A and B are similar in construction, each having an annular chamber 30 with four ports 31 31 and 32 32. The ports 31 31 of one valve are arranged at an angle of forty-five degrees from the 65 ports 31 31 of the other valve, as shown in

Figs. 6 and 7. The casing 28 has two ports 33 33 for the valve A and two ports 34 34 for the valve B, and when the valve B stands, as shown in Fig. 6, with its ports 31 31 in register with ports 34 34 the ports 31 31 and 32 32 of the valve A are all out of register with ports 33 33. Thus valve A is shut when valve B is open, and vice versa. An indicator 35 is arranged on the valve-shaft 22 and is housed within a casing 36, the latter having a sight-opening 37, through which the position of the indicator, and consequently the valve, may be learned. The outer end of the shaft 22 has a handle 38. Loosely mounted on the shaft 11 is a shrouded ratchet-wheel 39, having one unshrouded tooth 40 and having one tooth cut away to form a recess 42, and preferably formed integrally with the ratchet-wheel 39 is a cam 42, also loose on the shaft 11. Slidably mounted in the box 10 below the ratchet-wheel 39 is a pawl-carrier 43, guided by a stud 44 and operatively connected by a pin 45, which extends through a slot 46 in the box 10 with an operating-rod 47, the other end of the rod being connected with a lever 48, pivoted to the equalizing-bar 7 and having a spring-pressed arm 48^a, adapted to spring down freely, but to operate the lever 48 when the arm 48^a is moved upwardly. Interposed between a flange 49 on the rod 47 and an abutment 50 on the equalizing-bar is a coil-spring 51 for pushing the rod 47 rearward. A pin 52 on one of the front wheels 53 has a path of movement, which as the wheel revolves during the forward but not the backward movement of the car causes it to tilt the bell-crank lever 48 and move forward the operating-rod 47 once for each revolution of the wheel. Slidably mounted on the bottom of the box 10 and guided by a stud 54 is a block 55, having wings 56, and journaled in the wings 56 is a shaft 57, to which are keyed a pawl 58 and an arm 59. The pawl 58 has a lug 60, and a flat spring 61, bearing against the under side of the arm 59, serves to hold the arm and pawl elevated. Projecting below the pawl-carrier 15 is a hook 62, which is normally engaged by the pawl 58, as shown in Fig. 3. Fastened to the block 55 is a piston-rod 63, having a piston 64, which is mounted in a cylinder 65, a coil-spring 66 being interposed between the piston and a guide-block 66^a and serving to normally hold the piston retracted. The rear end of the cylinder has an air-passage 67, which communicates with a pipe 68. Pivoted to the end of the rod 47 is a pawl 69, which normally plays freely back and forth in the recess 42 without moving the ratchet-wheel 39, as the pawl-carrier 43 is reciprocated by the operating-rod 47. Fastened to the pawl-carrier 15 is a chain 70, and attached to the chain is a yoke 71, which is connected to two coil-springs 72, suspended from a supporting-yoke 73, carried by a screw 74, 130

by means of which the tension of the springs 72 may be regulated. The springs normally hold the pawl-carrier in the position shown in Fig. 3. When the piston 64 is moved forward by air-pressure, it advances the block 55, and the pawl 58, acting upon the hook 62, retracts the pawl-carrier and moves the pawl 19 back, so that it drops behind the next tooth of the ratchet 21. As soon as this occurs the lug 60 of the pawl 58 strikes a stop-screw 75, and a slight further movement of the block 55 causes the pawl 58 to disengage the hook 62, whereupon the springs 72, acting through the chain 70 upon the pawl-carrier 15 swings the arm 18 forward and the pawl 19 rotates the ratchet 21 the distance of one tooth and turns the valve-shaft 22, at the same time rotating the shaft 25 a corresponding amount.

Referring now to Fig. 2, 80 designates the valve for controlling the air-brakes, being connected to the pressure-pipe 81, a branch 82 of which connects it with the air-reservoir 83. 84 is the brake-cylinder, which is connected by a pipe 85 with the brake-pipe 86. The two valves A and B are designated by the semicircular dotted lines for clearness. One of the ports 33 of the casing of valve A is connected by a pipe a with the pressure-pipe 81. The other port 33 of the casing of valve A is connected by a pipe a' with the brake-pipe 86. One of the ports 34 of the casing of valve B is connected by a pipe b with the brake side of the controlling-valve 80. The other port 34 of the casing of valve B is connected by a pipe b' with the brake-pipe 86. A check-valve 87 is provided in the brake-pipe 86 between the pipe b' and pipe a' and allows air to pass from the pipe a' to the brake-cylinder 84, but prevents air from passing from the pipe b' back into the pipe a'. A pipe 88 is connected with the pipe a' and with a signal, such as a whistle 89.

As before stated, when the valve A is open the valve B is closed, and vice versa. Under normal conditions valve A is shut and valve B is open, so that the motorman has control of the brakes. When he opens the valve 80 to admit air from pipe 81 to pipes b b', pipes 86 and 85 to the brake-cylinder 83, thus setting the brakes, the air is prevented from passing back into the pipe a' and pipe 88 and blowing the whistle and also is prevented from backing into the pipe 68 and into the cylinder 65 by the check-valve 87. The pipe 68, before described, which admits air behind the piston 64, is connected to the pipe a'. When the apparatus is operated automatically and the valve A is opened and the valve B is shut, air from the reservoir 83 passes through the pipes 82 and 81, through the pipe a, through valve A, through pipe a', (incidentally through pipe 88, blowing the whistle,) through the check-valve 87, and

pipes 86 and 85 to the brake-cylinder, thus 65 automatically applying the brakes.

A circuit-breaker 90 is mounted beneath the car, as shown in Fig. 1, and comprises a base 91 with terminals 92 and 93, a blade 94 being hinged to the terminal 92. When the 70 blade 94 is in contact with the terminal 93, the circuit through the motors of the car is closed, while when the blade 94 is out of contact therewith the circuit through the motors is opened. The blade has a wing 95 with a 75 slot 96, into which projects a pin 97, which is carried by a disk 98, revoluble on a shaft 99. The disk 98 has a shoulder 100, which is adapted to be engaged by a pivoted detent 101. The detent 101 is provided at one side 80 with a curved face 102, while the detent 101 is yieldingly held against the edge of the disk 98 by a spring 103. The disk has a lug 104. Rigidly mounted on the shaft 99 is a winding-disk 105, to which is attached one end of a 85 coil-spring 106, the other end of the spring being attached to the disk 98. A long arm 107 projects from the disk 105, its end having a path of movement to engage the lug 104. The winding-disk 105 has two teeth 108 90 109, either of which may be engaged by a detent 110, which is held in operative position by a spring 111. The shaft 99 carries a bevel-gear 112, which meshes with a bevel-gear 113 on a shaft 117, having at its upper end 95 a crank 118, arranged in a position convenient to the motorman.

A pair of symmetrical detents 119 and 120 are pivoted to an insulated short shaft 121. Also pivoted to the shaft 121 is a block 122, 100 having a pair of studs 123. The detents 119 and 120 each have an arm 124, the two arms being connected together by a spring 125, which yieldingly holds both arms against the studs 123, as shown in Fig. 9.

A shaft 126 has its upper end pivoted in a plate 127, which is attached to the base 90, the lower end of the shaft being connected by a universal joint 128 with a slip-sleeve 129, which telescopes with the upper end of the 110 shaft 25, before described. The plate 127 has a slot 130, in which the upper end of a controlling-bar 131 freely plays up and down, the lower end of the bar 131 having a stud 132, which projects into a slot 133, formed in 115 the end of the block 122. A cam 134 is carried by the shaft 126 and has a cam-groove 135, into which projects a pin 136, which is carried by the bar 131. The groove 135 is formed with four upper convolutions and 120 four lower convolutions, and when the cam is rotated it reciprocates the bar 131 and tilts the detents 119 and 120. When the bar 131 is raised, the detent 119 stands in the position shown in Fig. 9 under the end of the 125 blade 94, holding the latter closed. The blade is always in a condition such that if freed by the detent it will spring out from

contact with the clip 93, as will shortly be described. Thus if the cam 134 is rotated the detent 119 will be tilted out from under the end of the blade 94 as soon as the cam has turned one-eighth around, and the blade 94 will spring out and bending back, the detent 120 stretching the spring 125, will be caught and held open by the detent 120 as the latter is sprung back by the spring 125. When the cam 134 turns another eighth, it obviously restores the block 122 and detents 119 and 120 to the position shown in Fig. 9, thereby drawing the detent 120 away from the end of the blade 94 and allowing the blade to be closed, during which closing of the blade the detent 119 is bent back, thereby stretching the spring 125 and being caught and held closed by the springing back of the detent 119. If now the cam 134 be rotated automatically, as before described, to raise the bar 131 and shift the detent 120 out of engagement with the blade 94, the blade will not automatically spring back into the clip 93, though the spring 106 is under tension, for the reason that the disk 98 is prevented from rotating by the detent 101. At this time, however, the motorman may reset the circuit-breaker and close the blade 94 by turning the crank 118, which will rotate the shaft 114 and shaft 99, together with the winding-disk 105, in the direction of the arrow 110. This will increase the tension of the spring 106, as the disk 98 is still held stationary by the detent 101, and during this movement the blade 94 still remains stationary; but as soon as the arm 107 has been moved around far enough to strike the curved face 102 it tilts the detent 101 out of engagement with the shoulder 100, whereupon disk 98 being released the latter is quickly moved by the spring 106 in the direction of the arrow, Fig. 9, and through the pin 97 closes the blade 94, the blade 94 being immediately locked in closed position by the detent 119. The blade now being locked, it prevents further rotation of the disk 98. The motorman cannot continue to turn the crank 118 farther from the point at which this action takes place than to bring the arm 107 into contact with the stop-lug 104, which being on the now rigidly-held disk 98 prevents further winding of the crank. Therefore as soon as the motorman releases the same the reaction of the spring 106 will retract the disk 105 slightly until it is arrested by the tooth 108 engaging the detent 110. While the circuit-breaker may thus be reset in the foregoing manner when the cam 134 is in a position which holds the bar 131 elevated, the circuit-breaker cannot be reset in this manner by means of the crank 118 if the cam 134 stands in a position such that the bar 131 is in its lowest position, because when the bar 131 is in that position the detent 120 holds the blade 94 open and the disk 98 is thus locked against rotation

through the medium of the gearing operated by the crank 118. The blade 94 can in this event only be reset by the motorman leaving his post at the controller and descending to the ground, manually releasing the blade 94 by springing back the detent 120.

Having described the construction and operation of the parts in detail, the operation of the apparatus considered as a whole will be described.

The apparatus is normally set as shown in the respective figures of the drawings, the blade 94 being shut, thus closing the circuit through the motors of the car and being retained in place by the detent 119. The valve B is open and the valve A is shut. As the car moves along, wheel 53, through its pin 52, operating upon the bell-crank 48, causes the operating-rod 47 to be constantly reciprocated, thereby reciprocating the pawl 69; but as the ratchet-wheel 39 stands in the position shown in Fig. 3 the pawl 69 moves freely back and forth in the recess 42, so that ratchet 39 is not operated. Thus, although as the car travels the pawl 69 is constantly operated, together with its operating-rod 47 and described connections, no other part of the apparatus is in operative movement under ordinary circumstances. When the operating-shoe 14 strikes a raised trip-lever, it is swung back, thereby rotating the shaft 11 in the direction of the arrow, Fig. 3, which retracts the arm 18, so that the pawl 19 drops behind the next tooth of the ratchet 21, whereupon the springs 72 contract and pull the chain 70 which turns the pawl-carrier 15 and moves forward the arm 18, which through the pawl 21 turns the valve-shaft 22 one-eighth of a revolution, which opens the valve A and closes the valve B. When the pawl 19 was retracted, as just described, the pawl 20 was also moved back, so that it dropped into the unshrouded tooth-recess 40, and as the arm 18 moved forward the pawl 20 turned the ratchet-wheel 39 the distance of one tooth, which caused the tooth behind the recess 42 to be moved into engagement with the pawl 69, so that the ratchet 39 is now being operated by the pawl 69 if the car moves. When the valve A is opened, air from the pressure-pipe 81 passes through the pipe a, through the valve A, through the pipe a', and pipe 88, thereby blowing the whistle 89, and through the pipes 86 and 85 to the brake-cylinder 84, which automatically applies the brakes. The brakes, however, are only applied temporarily in this case, as some of the air which is admitted through the pipe a' passes down through the pipe 68, through the air-passage 67, into the cylinder 65 and pushes the piston 64 forward, which through the piston-rod moves forward the block 55, so that the pawl 58 acting upon the hook 62 rocks the pawl-carrier 15 and arm 18 a second time to the right, allowing the pawl 19

to engage another tooth of the ratchet 21, at which time the pawl 58 is freed from the hook 62 by striking against the stop 75, whereupon the springs 72 contract and pull 5 upon the chain 70, which retracts the pawl-carrier 15, and the latter, through the pawl 19, rotates the ratchet 21 and operates the valve-shaft 22, shutting the valve A and opening the valve B, thus placing the brake 10 system again under the control of the motorman. At the same time that the valve-shaft 22 is operated, as just described, the shaft 25 is also turned, which, acting through the sleeve 29, rotates the shaft 126 and cam 134, 15 moving down the block 131 and tilting the detent 119 out of engagement with the circuit-breaker blade 94, whereupon the latter springs out, as before described, and breaks the circuit through the motors. Before the 20 motorman can proceed under power he must restore the blade 94, which may be done, as before described, by operating the crank 118. Obviously this opening of the circuit and application of the brakes checks the car in its 25 travel as a precaution at the first raised signal and allows the car to proceed at the discretion of the motorman. Assuming that the motorman decides to proceed, as the car moves along the ratchet-wheel 39 is operated 30 step by step by the pawl 69, as the latter is constantly reciprocated by the mechanism operated by the moving car-wheel 53 until the recess 42 comes into conjunction with the pawl 69, whereupon the ratchet 39 stops rotating, as it is in its ordinary normal position. 35 The parts may thus resume their normal position if a raised trip-lever is not met before the ratchet 39 gets to normal position. Upon encountering the next raised trip-lever the 40 foregoing operation will be repeated, and this operation will occur whenever a raised trip-lever is encountered when the ratchet 39 is in normal position, so that the pawl 69 plays freely in the recess 42. If, however, 45 the second-raised trip-lever is encountered before the ratchet-wheel has turned to its normal position, as soon as the shoe 14 rotates the shaft 11 it causes the valve A to be opened and the valve B to be closed. The 50 piston 64 will be moved forward by the air-pressure admitted through the pipe 68; but the pawl 58 will miss the hook 62 as it will be held down by reason of the arm 59 having been depressed by the cam 41. Thus the 55 pawl-carrier 15 will not be given the second automatic actuation to shut the valve A and open the valve B, and thus the brakes will be applied and the control will be removed from the motorman, as his control of the 60 brakes is exercised only when the valve A is shut and the valve B is open. At the same time, as when the valve A is open, the block 131 is in its lowest position and cannot raise, the circuit-breaker blade 94 will be held open 65 by the detent 120 and it will be impossible, as before described, for the motorman to restore the circuit-breaker blade by operating the crank 118. It thus becomes necessary before the car can proceed to reset the apparatus, and it is purposely designed to prevent the motorman from setting the apparatus in this manner the second time from the car and to compel him to get off the car in order to reset the circuit-breaker. The 70 valve-operating apparatus can be reset by manually manipulating the handle 38, which operation of the handle also places the cam 134 in such position that the circuit-breaker blade may then be reset by operating the crank 118. Thus by arranging the trip-levers 1 at intervals apart such that the car in traveling from one raised trip-lever to another will not have moved the ratchet 39 around to normal position. If two raised trip-levers are encountered in succession, the 75 car will when encountering the first trip-lever be warned by the opening of the circuit and by the setting of the brakes, which are almost immediately thereafter released, and if the car then proceeds after this precautionary measure upon encountering the succeeding trip-lever which is raised the brakes will be set without being immediately thereafter released automatically as before and that car cannot proceed until the apparatus 80 has been reset from the ground, as before described. The advantage of this arrangement is this: In a block system the car might encounter a raised trip-lever, which would give the signal and temporary setting 85 of the brakes and not fly the motorman that he was in the danger zone of the car ahead of him. The motorman on the rear car might proceed at his discretion, and if the car ahead has cleared the trip-lever which immediately 90 succeeds the trip-lever which has just set the apparatus on the rear car then the rear car can proceed freely without being hampered by a complete stoppage necessitating a resetting of the apparatus from the ground. 95 If the car ahead has not cleared the succeeding trip-lever, then the rear car will be absolutely brought to a stop and an accident avoided. Another advantage is that if the car is checked by a raised trip-lever early in 100 the day the apparatus will clear itself automatically, so that if another trip-lever is encountered later in the day the same warning and temporary setting of the brakes only 105 will be given. Otherwise if the apparatus 110 does not automatically clear or reset itself, as described, after encountering the raised trip-lever early in the day the car would be absolutely stopped when next encountering a raised trip-lever later in the day, which latter 115 raised trip-lever, being only a precautionary trip-lever, would result in considerable confusion. Thus in order to bring the car posi- 120 125

tively to a stop by this arrangement the car must encounter two adjacent raised trip-levers in succession.

When the apparatus is applied to a locomotive, it may be arranged as shown in Fig. 8, in which arrangement the throttle-valve 150 is substituted for the circuit-breaker. The throttle-valve 150 is operated by a bell-crank lever 151, which may be connected to a rod 152, the rear end of which may have a perforated block 153. The pivoted throttle-lever 154 may have pivoted thereto a detent 155, the vertical position of which detent may be regulated by a slotted bar 155^a. The bar 155 may be operated by a rod 156, and the rod 156 may be operated by a lever 157, which in turn may be operated by a cam 158, similar to the cam 134 before described. The apparatus for operating the cam 158 and air-brakes of the train may be similar to the apparatus previously described for operating the cam 134 and air-brakes of the electric car. The detent 155 normally engages the block 153, so that by manipulating the throttle-lever 154 the throttle-valve 150 may be regulated. When, however, the cam 158 is operated by reason of the shoe 14 encountering a raised trip-lever, the block 155 is drawn down by the rod 156, thereby drawing the detent 155 out of engagement of the block 153 and allowing the throttle-valve 150 to be automatically closed by a spring 159. When the block 155 is automatically raised by reason of the cam 158 automatically assuming its normal position as described with reference to the electric-car system, the detent 155 is thereby raised and takes into the block 153, thus restoring the connection between the throttle-lever and throttle-valve. Obviously if the shoe 14 encounters two trip-levers in succession the cam 158 will hold the block 155 down, so that it will be impossible for the engineer to open the throttle and start up the train until after the apparatus has been reset from the ground. In order to prevent the engineer from directly operating the block 153, the detent mechanism may be incorporated.

What I claim is—

- 50 1. A motor-circuit, a circuit-breaker for controlling said circuit, and means back of a wheel and substantially in line therewith and operated by a trip-lever on the track for opening said circuit-breaker.
- 55 2. Brake apparatus, and means back of a wheel and substantially in line therewith and operated by a trip-lever on the track for operating said brake apparatus.
- 60 3. A motor-circuit, a circuit-breaker in said circuit, brake apparatus, and means back of a wheel and substantially in line therewith and operated by a trip-lever on the track for operating the circuit-breaker and brake apparatus.
- 65 4. A signal, and means back of a wheel and

substantially in line therewith and operated by a trip-lever on the track for operating the signal.

5. A motor-circuit, a circuit-breaker in the circuit, brake apparatus, a signal, and means back of a wheel and substantially in line therewith and operated by a trip-lever on the track for operating the circuit-breaker, brake apparatus, and signal.

6. Car-stopping mechanism, and means back of the car-wheel and substantially in line therewith and operated by a trip-lever on the track for operating the car-stopping mechanism.

7. Car-stopping mechanism, means operated by the first-met protective trip-lever for temporarily applying said car-stopping mechanism, means operative from the car for resetting part of said car-stopping mechanism, and means operating automatically during the movement of the car for resetting the remainder of the car-stopping mechanism.

8. Means for checking the movement of a car, means operated by a protective trip-lever for causing the first means to check the speed of the car, and means automatically operating by the movement of the car for releasing said checking mechanism.

9. A car, brake apparatus therefor, means operated by a protective trip-lever for setting the brake apparatus, and means operating by the movement of the car for automatically subsequently releasing the brake apparatus.

10. A car, brake apparatus therefor, means operated by a protective trip-lever for setting the brake apparatus, means operating by the movement of the car for automatically subsequently releasing the brake apparatus, and means operated by a later-met protective trip-lever for again finally setting the brake apparatus.

11. Brake apparatus, means operated by the first-met protective trip-lever for temporarily setting the brake apparatus, means operated by the second-met trip-lever if in protective condition for again finally setting the brake apparatus, and means operated by the third-met trip-lever, if the second-met trip-lever was not in protective condition for temporarily setting the brake apparatus again.

12. A motor-circuit, a circuit-breaker in the circuit, means operated by the first-met protective trip-lever for snapping open the circuit-breaker, means operative from the car for restoring said circuit-breaker, and means operated by the next-met protective trip-lever for again opening the circuit-breaker.

13. A motor-circuit, a circuit-breaker in the circuit, means operated by the first-met protective trip-lever for opening the circuit-breaker, means operative from the car for restoring said circuit-breaker if the second-met trip-lever is non-protective, and means operated by the third-met protective trip-

lever for again opening the circuit-breaker if the said second-met trip-lever was not in protective position.

14. A motor-circuit, a circuit-breaker in the circuit, means operated by the first-met protective trip-lever for opening the circuit-breaker, means operative from the car for restoring said circuit-breaker, and means operated by the second-met trip-lever if in protective position for preventing the restoring of the circuit-breaker from the car.

15. In car-stopping apparatus, a motor-circuit, a circuit-breaker in the circuit, brake apparatus, means operated by the first-met protective trip-lever for snapping open said circuit-breaker and for applying the brake apparatus, and means operative from the car for restoring said circuit-breaker.

16. In car-stopping apparatus, a motor-circuit, a circuit-breaker in the circuit, brake apparatus, means operated by the first-met protective trip-lever for opening said circuit-breaker and for temporarily applying the brake apparatus, means operative from the car for restoring the circuit-breaker, means for again opening the circuit-breaker and applying the brake apparatus if the second-met trip-lever is in protective position.

17. In car-stopping apparatus, a motor-circuit, a circuit-breaker in the circuit, brake apparatus, means operated by the first-met protective trip-lever for temporarily applying the brake apparatus, means operative from the car for restoring the circuit-breaker, means operated by the second-met protective trip-lever for again applying the brake apparatus and opening the circuit-breaker and for preventing the resetting of the circuit-breaker from the car, and means operative from a point other than on the car for resetting the brake apparatus.

18. In car-stopping apparatus, a motor-circuit, a circuit-breaker in the circuit, brake apparatus, means operated by the first-met protective trip-lever for temporarily applying the brake apparatus, means operative from the car for restoring the circuit-breaker, means operated by the second-met protective trip-lever for again applying the brake and opening the circuit-breaker and for preventing the resetting of the circuit-breaker from the car, and means operative from a point other than on the car for resetting the brake apparatus and for placing the circuit-breaker in condition to then be reset from the car.

19. In car-stopping apparatus, a signal, means operated by a protective trip-lever for operating the signal, and means operating automatically by the movement of the car for stopping the operation of the signal.

20. In car-stopping apparatus, a signal means operated by a protective trip-lever for temporarily operating the signal, means operated by the next-met trip-lever if in protective position for again operating the signal,

and means operative from a point other than on the car for stopping the operation of the signal.

21. In car-stopping apparatus, brake mechanism, a motor-circuit, a circuit-breaker in the circuit, a valve for controlling the brake mechanism, means connected with the valve for controlling the circuit-breaker, and means operated by a protective trip-lever for actuating said valve once, and means operated by fluid-pressure for automatically subsequently operating the valve a second time.

22. In car-stopping apparatus, brake mechanism, a motor-circuit, a circuit-breaker in the circuit, a valve for controlling the brake mechanism, means connected with the valve for controlling the circuit-breaker, means operated by the first-met protective trip-lever for actuating said valve once, means operated by fluid-pressure for automatically subsequently operating the valve a second time, means operated by the second-met trip-lever if in protective position for operating the valve a third time and means for preventing the fluid-pressure means from subsequently operating the valve.

23. In car-stopping apparatus, brake mechanism, a motor-circuit, a circuit-breaker in the circuit, a valve for controlling the brake mechanism, means connected with the valve for controlling the circuit-breaker, means operated by the first-met protective trip-lever for actuating said valve once, means operated by fluid-pressure for automatically subsequently operating the valve a second time, means operated by the second-met trip-lever if in protective position for operating the valve a third time and for preventing the fluid-pressure means from subsequently operating the valve, and means for normally operating the valve, and means for again operating the valve from a point other than on the car.

24. In car-stopping apparatus, brake mechanism, a motor-circuit, a circuit-breaker in the circuit, a valve for controlling the brake mechanism, means connected with the valve for controlling the circuit-breaker, a ratchet-wheel connected with the valve, a pawl for operating the ratchet, means operated by a protective trip-lever for operating said pawl and fluid-pressure means for subsequently again operating the pawl.

25. In car-stopping apparatus, brake mechanism, a motor-circuit, a circuit-breaker in the circuit, a valve for controlling the brake mechanism, means connected with the valve for controlling the circuit-breaker, a ratchet-wheel connected with the valve, a pawl for operating the ratchet, means operated by the first-met protective trip-lever for operating said pawl, fluid-pressure means for subsequently again operating the pawl, means operated by the second-met trip-lever if in protective position for again operating the pawl, and means for preventing the subsequent op-

eration of the pawl by the fluid-pressure means.

26. In car-stopping apparatus, brake mechanism, a valve for controlling the brake mechanism, and means operated by a protective trip-lever for actuating said valve once, and means operated by fluid-pressure for automatically subsequently operating the valve a second time.

27. In car-stopping apparatus, brake mechanism, a valve for controlling the brake mechanism, means operated by the first-met protective trip-lever for actuating said valve once, means operated by fluid-pressure for automatically subsequently operating the valve a second time, means operated by the second-met trip-lever if in protective position for, operating the valve a third time and means for preventing the fluid-pressure means from subsequently operating the valve.

28. In car-stopping apparatus, brake mechanism, a valve for controlling the brake mechanism, means operated by the first-met protective trip-lever for actuating said valve once, means operated by fluid-pressure for automatically subsequently operating the valve a second time, means operated by the second-met trip-lever if in protective position for operating the valve a third time and for preventing the fluid-pressure means from subsequently operating the valve, and means for manually again operating the valve from a point other than on the car.

29. In car-stopping apparatus, brake mechanism, a valve for controlling the brake mechanism, a ratchet-wheel connected with the valve, a pawl for operating the ratchet, means operated by a protective trip-lever for operating said pawl, and fluid-pressure means for subsequently again operating the pawl.

30. In car-stopping apparatus, brake mechanism, a valve for controlling the brake mechanism, a ratchet-wheel connected with the valve, a pawl for operating the ratchet, means operated by the first-met protective trip-lever for operating said pawl, fluid-pressure means for subsequently again operating the pawl, means operated by the second-met trip-lever if in protective position for again operating the pawl, and means for preventing the subsequent operation of the pawl by the fluid-pressure means.

31. In car-stopping apparatus, brake mechanism, a valve for controlling the brake mechanism, a ratchet-wheel on the valve, a pawl-carrier, a pawl on the pawl-carrier for operating the ratchet, means operated by a trip-lever for actuating the pawl-carrier, a cylinder, a piston therein, means carried by the piston-rod for actuating the pawl-carrier, and means for conveying fluid-pressure from said valve to said cylinder.

32. In car-stopping apparatus, brake mechanism, a valve for controlling the brake

mechanism, a ratchet-wheel on the valve, a pawl-carrier, a pawl on the pawl-carrier for operating the ratchet, means operated by a trip-lever for actuating the pawl-carrier, a cylinder, a piston therein, a hook on the pawl-carrier, and means operated by the piston for engaging the hook and operating the pawl-carrier.

33. In car-stopping apparatus, brake mechanism, a valve for controlling the brake mechanism, a ratchet-wheel on the valve, a pawl-carrier, a pawl on the pawl-carrier for operating the ratchet, means operated by a trip-lever for actuating the pawl-carrier, a cylinder, a piston therein, a hook on the pawl-carrier, and means operated by the piston for engaging the hook and operating the pawl-carrier, and means operating automatically during the movement of the car for preventing said piston-operated means from engaging said hook.

34. In car-stopping apparatus, brake mechanism, a valve for controlling the brake mechanism, a ratchet-wheel on the valve, a shaft, a pawl-carrier mounted loosely on the shaft, a pawl on the pawl-carrier for operating the ratchet, means on the shaft for rocking the pawl-carrier, a hook on the pawl-carrier, a slide-block, fluid-pressure means for moving the slide-block, a pawl carried by the slide-block for engaging the hook, a ratchet mounted on said shaft and having a tooth-recess, a pawl normally freely playing in said recess, means for automatically reciprocating the pawl as the car moves, all but one of the teeth of the second ratchet being shrouded, a dog on the pawl-carrier normally resting on the shrouded rim, a cam carried by the second ratchet, and means operated by said cam for controlling the pawl which engages said hook.

35. In a car-stopping apparatus, brake mechanism, a revoluble valve for controlling the brake mechanism, a ratchet carried by the valve, a pawl for operating the ratchet, a pivoted pawl-carrier, means for rocking the pawl-carrier in one direction, and means for retracting the pawl-carrier comprising a chain attached to the pawl-carrier, a yoke attached to the chain and springs connected to the yoke.

36. In a car-stopping apparatus, brake mechanism, a revoluble valve for controlling the brake mechanism, a ratchet carried by the valve, a pawl for operating the ratchet, a pivoted pawl-carrier, means for rocking the pawl-carrier in one direction, and means for retracting the pawl-carrier comprising a chain attached to the pawl-carrier, a yoke attached to the chain and springs connected to the yoke, a yoke for supporting the springs, and a screw-bolt passing through the latter yoke for adjusting the tension of the springs.

37. In car-stopping apparatus, brake mechanism, a valve for controlling the brake

- mechanism, a ratchet on the valve, a pawl for operating the ratchet, a shaft, a lug on the shaft, a pawl-carrier on the shaft and having a segmental recess into which said lug projects, means operated by a trip-lever for rocking the shaft and actuating the pawl-carrier, and additional means for automatically rocking the pawl-carrier independently of the shaft.
38. In a car-stopping device, a motor-circuit, a circuit-breaker in said circuit embracing a blade, means for maintaining a pressure on the blade tending to open it, a detent engaging the blade and holding it shut, and means operated by a trip-lever for releasing the detent.
39. In a car-stopping device, a motor-circuit, a circuit-breaker in said circuit embracing a blade, said blade having a slot, an operating-disk, a pin carried thereby and projecting into the slot, a winding-disk, a coil-spring connecting the winding-disk and the operating-disk, a detent normally holding the winding-disk from unwinding, a cam, a shaft, a pair of detents mounted on the shaft, a block pivoted on the shaft, a pair of studs on the block, means for yieldingly holding portions of said detents against said studs, a bar loosely connected with said block, a pin on the bar working against said cam, and means operated by a trip-lever for turning said cam.
40. In a car-stopping device, a motor-circuit, a circuit-breaker in said circuit embracing a blade, said blade having a slot, an operating-disk, a pin carried thereby and projecting into the slot, a winding-disk, a coil-spring connecting the winding-disk and the operating-disk, a detent normally holding the winding-disk from unwinding, a cam, a shaft, a pair of detents mounted on the shaft, a block pivoted on the shaft, a pair of studs on the block, means for yieldingly holding portions of said detents against said studs, a bar
- loosely connected with said block, a pin on the bar working against said cam, and means operated by a trip-lever for turning said cam, and means for normally turning said cam.
41. In car-stopping mechanism, brake apparatus, means operated by a protective trip-lever for temporarily applying the brake apparatus, a ratchet, means operating during the traveling of the car for operating said ratchet, and means operated by the next-met protective trip-lever for again applying the brake apparatus, and means operated by said ratchet for preventing the automatic resetting of the brake apparatus after the same has been applied by the second protective trip-lever.
42. In car-stopping apparatus, mechanism operated by a protective trip-lever for stopping the car, means for automatically releasing the first means, means operated by the travel of the car for restoring said mechanism and former means to normal condition at a point between the second and third met trip-levers if the second-met trip-lever is not in protective position.
43. In car-stopping apparatus, mechanism operated by a protective trip-lever for stopping the car, means for automatically releasing the first means, means operated by the travel of the car for restoring said mechanism and former means to normal condition at a point between the second and third met trip-levers if the second-met trip-lever is not in protective position and means for preventing the operation of the said second-named means when the car travels backward.
- In testimony whereof I have hereunto set my hand, at Los Angeles, California, this 15th day of July, 1905.
- ARTHUR D. SKILLMAN.
